UNITED STATES PATENT OFFICE.

WILLIAM LAMBERT, OF EAST POINT, GEORGIA.

FOOT REST FOR BEDS.

Application filed July 20, 1923. Serial No. 652,765.

To all whom it may concern:

Be it known that I, WILLIAM LAMBERT, a citizen of the United States, residing at East Point, in the county of Fulton and 5 State of Georgia, have invented a new and useful household article—namely, a Foot Rest for Beds—of which the following is a specification.

This invention relates to attachments for 10 beds and particularly to a device adapted to be inserted under the mattress at the foot of a bed for supporting the end of a mattress in an upwardly inclined position and also the bed clothes on the bed, so that they 15 will not exert a pull on the feet of the occupant of the bed.

An object of the invention is to provide a 20 device of the above mentioned character, having a pair of end blocks arranged in spaced parallel relation and connected by a plurality of spaced parallel strip members, one side of said end blocks being inclined, so that it will have a cross section of trapezoidal form, and when positioned on the 25 spring and adjacent the foot end of the bed, the inclined wall portion thereof will support the lower end of the mattress in an inclined position, in order to provide a comfortable rest for the feet of an occupant of 30 the bed, and at the same time support the covers thereon, so that they will not hang or pull on said occupant's feet, but will provide a space between the covers and the mattress for the occupant's feet, which will 35 make the bed more comfortable.

The invention includes other objects and 40 improvements in the details of construction and arrangement of the parts, which are more particularly pointed out in the following description and claim directed to the preferred form of the invention, it being understood however, that various changes in the size, form, and construction and arrangement of these parts may be 45 made, without departing from the spirit and scope of the invention as described and claimed.

In the drawing, forming a part of this application:

50 Figure 1 is a perspective view of the device.

Figure 2 is a perspective view of an end portion from below.

Figure 3 is an end elevation.

Figure 4 is a sectional view through the 55 foot portion of the bed, showing the device in place.

1 indicates end blocks, which are of trapezoidal section or form, in which the upper 60 and lower sides are parallel, one connecting 65 side wall indicated at 2 being vertical, and the other side wall 3 being inclined, for a purpose which will presently appear. The edges of these end blocks 1 have a plurality of strips 4 secured thereto, in spaced relation, for mounting said end blocks in parallel spaced relation at the end portions of the strip. If desired, a cover 5, such as illustrated in Figure 2 may be provided for the 70 device, in order to prevent the same collecting dust and dirt.

Figure 4 illustrates the manner of inserting the device above described at the foot of a bed, the vertical side 2 of the end blocks being directed adjacent and against 75 the foot portion of the bed, while the inclined sides 3 receives the lower end of the mattress and directs the same upwardly in inclined relation with respect to the remaining portion of the mattress, in order 80 to provide a support for the covers 6 on the bed, so that a pocket 7 will be formed between the covers and the inclined end portion of the mattress for the feet of the occupant of the bed, in a manner that the covers 85 will hang over the feet and not exert a pull or tension thereon, as is usual, where the end of the mattress lies on the springs. This device further forms a support for 90 the feet, through holding the mattress in inclined relation and also lessens the likelihood of the covers being pulled out from under the end of the mattress under the end of the bed, as is usual in the use of a mattress in the ordinary manner, where it 95 lies in a horizontal plane on the spring. In this way, it will be seen that the bed covers 6 hangs from the free edge of the mattress which is above the major portion thereof, in order to provide the pocket 7 for the 100 feet of an occupant, so that a comfortable arrangement of the cover results and in which the covers hang downwardly over the top of the feet.

It will thus be seen that a novel device 105 of relatively simple construction has been

provided, for increasing the comforts of a bed by properly supporting the covers over the feet of an occupant.

What is claimed is:

- 5 Means for supporting a mattress at the foot end of a bed, in inclined relation to the foot portion of the bed, for supporting the bed covers in a manner that said covers will hang over the feet of an occupant of
- 10 the bed; comprising a supporting member

having end members of trapezoidal form arranged in spaced parallel relation, and a plurality of spaced parallel strip members secured to said end members whereby the supporting member may be positioned adjacent the foot portion of the bed on the spring with an inclined face to receive and support the end of the mattress.

WILLIAM LAMBERT.
